UNITED STATES PATENT OFFICE.

ALBERT S. ANDERSON, OF ST. PAUL, MINNESOTA, ASSIGNOR TO GRANT WALDREF, OF ST. PAUL, MINNESOTA.

HYDRAULIC UNLOADER.

1,289,596.

Specification of Letters Patent. Patented Dec. 31, 1918.

Application filed June 30, 1915. Serial No. 37,194.

To all whom it may concern:

Be it known that I, ALBERT S. ANDERSON, a citizen of the United States, residing at St. Paul, in the county of Ramsey and State 5 of Minnesota, have invented a new and useful Improvement in Hydraulic Unloaders, of which the following is a specification.

My invention relates to improvements in hydraulic unloaders for vehicles, the primary object being to provide a simple, light, compact, durable and easily operated apparatus for tilting the body of a vehicle for the purpose of quickly dumping the contents thereof.

More particularly this invention relates to that class of hydraulic unloaders, wherein an impelling medium is circulated through a system of ducts for operating a piston which is associated with the tilting body 10 for raising and lowering said body. The subject matter of this application is an improvement upon the hydraulic dump, set forth in the application filed by Garfield A. Wood, on the 21st day of October, 1912, 15 Serial Number 726,929, and is directed more particularly to means whereby lateral thrust upon the operating parts of the device is compensated, so that the working parts move freely without any binding effort or unnecessary friction. This application does 20 not claim broadly the particular system of ducts employed for propelling the piston such structure being claimed in companion application executed this day by Grant Waldref to whom my application has been assigned.

In the accompanying drawings forming part of this specification, Figure 1 is a side elevation partly in section of my invention 25 showing part of an automobile chassis, and a portion of a tiltable body thereon; Fig. 2 is a side elevation partly in section of a detail of my improvement; Fig. 3 is a front elevation of a detail; Fig. 4 is a section on the line X—X of Fig. 1 with controlling handles and part of structure broken away; Fig. 5 is a section on the line Y—Y, Fig. 1; Figs. 6 and 7 are sections of details pertaining to valve mechanism by which the pump 30 is controlled in operation, and Fig. 8 is a perspective of a detail illustrating the manner in which the lifting cables are attached to the tiltable body of the vehicle.

In the drawings A indicates a portion of 35 a chassis of an automobile truck and B a

detail of the vehicle body which is tiltingly mounted upon the chassis in the customary manner, said body being provided with a pair of depending lifting arms, which are spaced apart on the front end of the body 60 as illustrated in Fig. 8. Mounted upon the chassis and secured thereto such as by bolts 2 and angle members 3 is a base 4 resembling a plate into which is threaded or otherwise fastened the upwardly extending hydraulic 65 cylinder 5, the lower end of said cylinder being connected with a passage 6 extending forwardly and upwardly through the base. In the cylinder is a piston 7 having a hollow piston rod 8 extending upwardly through 70 the packing flange 9, (see Fig. 4) in the upper end of the cylinder. The lower end of said rod is formed with passages 10 (see Fig. 1) entering the cylinder and rod, and the upper end of said rod carries a yoke 11 75 fitted closely thereto and provided with a passage 12 entering the piston rod, said passage containing an open threaded stopper 13. By removing the stopper 13, the cylinder can be filled with propelling fluid 80 through the piston rod. The yoke 11 carries on each of its arms which are spread laterally from the piston rod a pair of links 14. These links are freely hung from the yoke and carry sheaves 15 positioned on opposite sides of the cylinder and over which travel a pair of flexible lifting cables 16. The forward lower ends of these lifting cables are secured pivotally to an equalizer arm 17 pivoted midway between its ends by 85 a link 18 to a coupler 19, said coupler being in the form of a rod bent midway between its ends and having its ends secured permanently to the base 4. The equalizer compensates for any uneven side thrust against 90 the piston rod due to uneven loading of the body, uneven length of the lifting cables or slanting of the vehicle laterally. The rearward lower ends of the lifting cables are attached to the lifting arms 1. When the piston moves upwardly in the cylinder, the sheaves force the cables 16 upwardly between their ends, thus lifting the load by a short upward stroke of the piston. All of the parts as described are symmetrically arranged so as to assist in compensating uneven lateral strains and causing the piston and its rod to work evenly and smoothly with little or no binding effort or tendency.

Mounted upon the base 4 and secured by 110

bolts 20 is a gear pump C having a pair of intermeshing toothed pump gears 25 and 26 carried by shafts 27 and 28, which are journaled in the walls of the pump casing 29. 5 This pump casing is formed with a double cylindrical wall in which the gears revolve, the casing being provided with ingress and egress ports 30 and 31 for the pumping fluid. The pump casing is also formed with 10 a passage 32, which communicates with the passage 6 in the base and the egress port 31 and leads upwardly through the top of the casing to form a by-passageway. The casing is also formed with another passage 33 15 which leads from a port 30 upwardly through the top of the casing. Mounted upon the casing is a valve D which is seated in a valve housing 34. This valve housing is formed with a pair of passages 35 and 20 36 respectively connecting with the passages 32 and 33, in the pump casing and entering the valve seat in opposite position so as to be opened and closed independently by the valve. The valve housing also has another 25 passage 37 entering the valve seat with which a pipe 38 is connected by the coupling 39, said pipe being also connected with the upper end of the cylinder above the piston, the point of connection between the pipe 38 30 and the cylinder being a short distance below the upper extremity of the cylinder. Thus the valve seat has three separate ports leading respectively and ultimately to the upper and lower ends of the cylinder and 35 to the ingress opening of the pump chamber. The valve D is of rotary conical type mounted in the valve housing on the valve seat, and is provided with a stem 40 by which the valve can be rotated. This valve 40 is pressed firmly upon its seat to form a tight connection by means of a compression spring 41 bearing against its ends opposite said stem. The valve is formed with a 45 transverse passage 42. When the valve is moved into one position as illustrated in Fig. 6 the fluid is conducted and forced by the gear pump into the lower end of the cylinder, thus raising the piston and the load carried thereby. When the valve is 50 moved into the position illustrated in Fig. 7 a short continuous circuit is formed for the fluid around the pump through the passages 33, 32, 35 and 36 without forcing the piston upwardly. When the valve is moved 55 into the position illustrated in Fig. 5 and the pump stopped, the fluid instead of passing through the pump flows freely through the valve and the passage 32 independent of the pump, thus allowing the piston to descend 60 and return slowly into normal position, partly by the weight of the body B, and partly by gravity. The operation of the valve D is controlled by a handle in the form of a lever 45 pivoted upon a supporting member 46, which is secured to the cylinder 65

der 5. The free end of this lever handle has pivotally secured thereto a pitman 47, which in turn is pivoted to the free end of an arm 48 carried by the stem 40 of the valve, thus by raising and lowering the operating lever 45 the valve D is turned in its seat. 70

The pump C is driven by the driving element of the vehicle such as the usual propeller shaft 49. This propeller shaft has 75 secured to it the driving element 50 of a clutch which is adapted to communicate motion from the propeller shaft to a driven element 51, said driven element being feathered to a sprocket 52 around which a 80 sprocket chain 53 travels. This sprocket chain engages over a sprocket pinion 54 carried by the shaft 27 of the pump. Thus when the driven element 51 of the clutch is slid along the propeller shaft 49 into engagement with the driving element 50, power is transmitted to the gear pump and the gears 25 and 26 of the pump revolved. The driving element of the clutch carries a toothed shifting element 68 slidable 85 diametrically across the axis of the propeller shaft with the teeth of which the teeth 69 on the driven element 51 are engaged when the clutch is closed, said shifting element forming a universal coupling in the 90 clutch and compensating any uneven motion of the clutch elements and propeller shaft. The actuating means for throwing the clutch into and out of operation consists of a handle lever 55 pivoted upon the support 46 and connected by a pitman 57 to one arm 58 of a bell crank lever. This bell crank lever is pivoted at its angle upon a supporting bracket 59, which is attached to a depending support 60, in which the gear 100 member 52 is journaled. The other arm of the bell crank lever is freely connected by bifurcation 61 working in the channel 62 of a collar 63 journaled upon the sleeve 64 forming part of the driven element 51 of 105 the clutch, so that when the bell crank lever is tilted the driven member is thrown into or out of connection with the driving element and clutch. To hold the arm 55 of the clutch operating mechanism in adjusted 110 position with the clutch members in or out of engagement, the arm 55 is made to spring into releasable engagement with the teeth 65 of a quadrant 66 formed on the support 46. The lever arm 55 is flexibly mounted 115 upon the supporting member 46 and is releasably pressed into engagement with the teeth 65 on a side of the quadrant by a spring 67. 120

In operation after the cylinder and connecting passages have all been filled with oil or any other suitable impelling medium desired through the passage 12, the plug 13 is inserted in said passage. When it is desired to raise the body the clutch is thrown 130

into operation by raising the handle 55 until the driven member of the clutch is fully engaged with the driving member. Motion is then imparted by the propeller shaft 49 to the gears in the pump which in turn revolve in the direction of the arrows shown in Fig. 5 and propel the impelling medium in the pump. The valve operating handle 45 is then moved upwardly until the valve assumes the position indicated in Fig. 6, whereupon the impelling medium is forced upwardly into the cylinder and the piston raised until it moves above the passage in the wall of the cylinder to which the pipe 38 is connected. While the piston is rising the chamber in the piston rod supplies propelling medium to the pump, said chamber being open to the outer atmosphere allowing the fluid to pass freely to the pump as required to fill the space in the cylinder below the piston. Upon reaching uppermost position the body remains tilted while the pump continues in operation, the fluid thereupon passing continuously through the cylinder and back to the pump through the pipe 38. If the pump is then stopped the impelling medium below the piston holds the piston in superior position. To lower the body the pump is stopped and the valve is moved by swinging the handle 45 until it assumes the position illustrated in Fig. 5, whereupon the propelling medium escapes the pump gears and is conducted by passage 32 upwardly, allowing the piston to descend freely and slowly according to the valve opening. While the piston is lowering the impelling medium displaced below the piston in the cylinder fills the space above the piston and in the piston rod. Thus the piston rod acts as a displacement chamber as well as performing its usual function and the use of a tank or other chamber independent of the cylinder is obviated.

By providing the mechanism disclosed for

equalizing and compensating uneven lateral thrusts upon the parts and by arranging the parts symmetrically, even and smooth operation is imparted to the mechanism under the widely varying conditions required to which devices of this character are subject.

50

As a result of my invention the construction is simple, compact, light, durable and easily operated.

In accordance with the patent statutes, I have described the principles of operation 55 of my invention, together with the apparatus which I now consider to represent the best embodiment thereof, but I desire to have it understood that the construction shown is only illustrative, and that the invention can be carried out by other means and applied to uses other than those above set forth within the scope of the following claim.

60

Having described my invention, what I 65 claim as new and desire to protect by Letters Patent is:

A device of the type described, comprising, in combination, a vehicle having a tiltable body, a platform mounted upon the vehicle, a motor driven hydraulic cylinder mounted upon said platform and having a piston provided with an upwardly projecting piston rod, a yoke on the upper end of said rod, links hung from said yoke on opposite sides of said rod, sheaves journaled in said links, a compensator near the lower forward portion of said cylinder, a rod bent between its extremities having its ends attached to said platform, a link freely attached to the medial portion of said rod and the medial portion of said compensator, and flexible connections traveling over said sheaves and connected to said compensator and said tiltable body.
